UNITED STATES PATENT OFFICE.

JOSEPH F. D. HOGE, OF NEW YORK, N. Y., ASSIGNOR TO AMERICAN DISTRICT TELEGRAPH COMPANY, A CORPORATION OF NEW JERSEY.

MULTIPLEX TELEGRAPH SYSTEM.

1,030,780.

Specification of Letters Patent. Patented June 25, 1912.

Original application filed April 11, 1910, Serial No. 554,668. Divided and this application filed July 27, 1910, Serial No. 574,204.

To all whom it may concern:

Be it known that I, JOSEPH F. D. HOGE, a citizen of the United States, residing at New York, in the county of New York and State of New York, have invented a certain new and useful Multiplex Telegraph System, of which the following is a specification.

My invention relates to improvements in multiplex telegraph systems, and particularly call box signaling systems, such as district messenger systems, watchmen's systems, fire alarm systems, etc., and constitutes a specific form of the system illustrated and described in my application filed April 11, 1910, Sr. No. 554,668, of which application the present application is a division. I will particularly describe herein my invention, as applied to district messenger systems and like signaling systems, involving the use of call boxes (it being understood that fire alarm boxes and other like automatic telegraph transmitters are, in a general sense, the equivalent, in a system such as herein described, of district messenger call boxes) it being understood that in illustrating the embodiment of my invention in such a system, I do not limit it to use in such systems, but that it is applicable to general telegraphy as indicated in said application Sr. No. 554,668.

In district messenger systems, fire alarm systems, and the like, it is customary to provide a number of call boxes in a single circuit, these boxes adapted each to transmit a signal (usually a number) different from the signals of the other boxes in the same circuit, suitable receiving devices being located at what for convenience may be termed a "central station." In practice there are a number of such circuits leading to the same central station, and the call boxes or transmitting devices of each circuit are usually somewhat close together. There is a practical limit to the number of boxes that may be placed in any one circuit, and give good service, this number varying more or less according to local conditions, but since in general any such system will comprise circuit conductors of considerable length leading from the central station to the vicinity where the boxes are located, a considerable economy may be effected if these same conductors may be used for transmitting the

signals of an entirely distinct group of boxes, provided no interference between the signals of the different groups of boxes results. This I accomplish according to my present invention. I arrange to impose upon the same circuit conductors two distinct currents, one a direct current, the other an alternating current of somewhat high frequency, and I provide two groups of call boxes, one arranged to affect the direct current, the other to affect the alternating current; and I provide two distinct receiving devices, one for the direct current signals, the other for the alternating current signals. Between the direct current boxes and the line conductors, and between the direct current receiving devices and the line conductors, I provide means for preventing these instruments from being affected by, or from affecting, the alternating currents; and between the alternating current boxes and the line conductors and the alternating current receiving devices and the line conductors, I interpose means for preventing such devices from being affected by, or affecting, the direct currents. The direct current transmitting and receiving devices are already well known in the art.

The isolation of the several systems employing the same line conductors, according to my invention, depends (first) on the fact that an inductance coil can be constructed which for any given conditions will limit the passage of an alternating current through it to any desired value, however small, (though in practice such inductance coil cannot be made to actually exclude the alternating current altogether, but can be made to limit it to such value that it does not cause disturbance of the instruments); (second) on the fact that a condenser and an inductance coil placed in series in a circuit, may have the values of their capacity and inductance, respectively, so chosen, that they will have a very small impedance to an alternating current of a given frequency, but will offer a great impedance to one of a higher or lower frequency, the condenser being effective principally to exclude currents of lower frequency, the inductance coil being principally effective to exclude currents of higher frequency, so that it is possible to limit the passage of a second alternating current of

different frequency to any given value, however small, even though in practice it be impossible to exclude such second alternating current altogether, though possible to reduce it to such value that it does not produce material disturbance.

In essential principle, the exclusion of a direct current from the alternating current system or systems, is somewhat similar to excluding an alternating current of lower frequency from systems in which alternating currents of higher frequency are used, for while a condenser will pass no current for a constant direct potential after once charged, a pulsating direct current will give rise to an alternating current through the condenser, the condenser accepting current in one direction to charge it as the potential rises, and passing it in the opposite direction by discharging as the potential falls.

Heretofore in attempts to use alternating currents in telegraph and like signaling systems, embodying relays, difficulty has been experienced in obtaining good contacts at the contact points of relays operated by alternating currents; there being a tendency for the armature to leave the contact point at the instant of current reversal. According to my present invention I overcome this tendency, by the use, in connection with each such relay, of a current rectifier which transforms the electric current of the line into a direct current, in so far as the coils of the relay are concerned. Various types of these rectifiers are known, and I do not limit myself to any particular type though I have illustrated and described herein one type of such rectifier which I have found suitable for the purpose.

The objects of my invention are to increase the service capacity of telegraph, alarm, and other signaling circuits and the like, without detriment to the service given, to avoid conflict between the several superimposed signaling systems, to make the apparatus required simple, easily understood, easily adjusted, and relatively inexpensive, to make the complete system operate correctly either over a metallic circuit or over ground return circuits, and to provide for the conversion at will of a metallic circuit system into two independent ground return systems, and vice versa, and to make the system as a whole operative with currents of low potential and with instruments of a simple and relatively inexpensive type.

I will now proceed to describe my invention with reference to the accompanying drawings, illustrating more or less diagrammatically different arrangements of circuits and instruments embodying my invention.

In said drawings: Figure 1 shows diagrammatically a call box system comprising a direct current side and an alternating current side, using the same line conductors

and operating normally through a metallic circuit but adapted at will to be changed into two separate systems comprising each a line conductor and a ground return; Fig. 2 shows an elevation and partial section of a rectifier such as is illustrated diagrammatically in Fig. 1.

Referring now to the drawings, and at first to Fig. 1, 1 and 2 designate line conductors, serving both for the primary or direct current signaling circuit and for the alternating current circuit, before referred to. 3, 3 designate ordinary call boxes, *i. e.*, signal transmitters, in a primary circuit 4 connected to the line conductors 1 and 2 through inductive resistances 5; and 6 designates a corresponding direct current receiving set, at a central station, connected to line conductors 1 and 2 through inductive resistance 7. The call boxes 3 are to be understood to be of any well known type and for ordinary call, signal, or alarm service are preferably arranged to work according to the well-known McCulloh system, each having, as is customary in such boxes, two signal wheels of similar signal numbers, one arranged to work through the metallic circuit, the other to work through a ground return, each such box having a ground connection 8. The receiving set 6 is of the general nature of such sets as commonly employed in district telegraph work, comprising receiving relays 9 and 10, (in this system usually having resistance of from 600 to 1000 ohms) a receiving register 11, and a further receiving device 12, also a double-throw multi-pole switch 13, commonly termed a McCulloh switch in a system such as this, by which the circuit comprising conductors 1 and 2 may be converted, at will, into two separate ground-return circuits, according to the well-known McCulloh system. The general arrangement of the instrument of the receiving set 6, shown in the drawings, is that of the patent to Hamblin N°. 808,451, dated Dec. 26, 1905. 14 designates a direct-current generator, 14^a another direct-current generator supplying current to the local circuit of receiving sets 6 and 20, and 15, 15^a suitable non-inductive resistances of from 250 to 300 ohms—in any case, a resistance high enough to make resistance, rather than inductance, the controlling factor in the local circuits of the direct-current receiving set 6. Otherwise, the inductance of the local direct-current receiving apparatus would delay the current rise and fall and so prevent it responding to impulses of short duration in the desired manner.

16, 16 designates call boxes similar to boxes 3, but located in a circuit 17 connected to conductors 1 and 2 respectively, through condensers 18 and inductive resistances 19. 20 is a receiving set, for boxes 16, arranged to be operated by alternating cur-

rents of relatively high frequency, and connected to conductors 1 and 2 through condensers 21 and inductive resistances 22.

23 designates an alternating current generator for supplying current to receiving set 20 and boxes 16.

Receiving set 20 is in general the same as set 6, comprising relays 24 and 25, a register 26, another signal receiving device 27, and 10 a double-throw multi-pole McCulloh switch 28, by which the circuit 17, the alternating current of which is superimposed upon the direct current of circuit 4 flowing through conductors 1 and 2, may be converted, at 15 will, into two separate ground-return circuits, according to the well-known McCulloh system. It is found practically nearly impossible to work ordinary direct-current relays on alternating currents of the frequencies which I propose to use in this system, without employing special adapting means, as hereinafter described, since such relays, if operated by such currents, do not produce sufficiently good contacts between 20 their armatures and front contact points, owing to the constant alternate magnetization and demagnetization of their magnets and the constant pull upon their armatures of the customary retractile springs. Hence 25 I employ in connection with these relays, rectifiers 24^b and 25^b. I do not limit myself to any particular type of rectifier but have found a three cell electrolytic rectifier of well known type, indicated diagrammatically in Fig. 1, to be effective; and in 30 Fig. 2 I have illustrated one of the cells of such a rectifier. It comprises electrodes 34 and 35, electrodes 34 being customarily of iron and electrode or electrodes 35 being 35 customarily of aluminum. I have indicated diagrammatically in Fig. 1, in connection with each of relays 24 and 25, such a three-cell rectifier, having each one aluminum electrode and one iron electrode, while the 40 intermediate cell has usually two aluminum and one iron electrode. For an electrolyte I have found a solution composed of one part borax, two parts concentrated ammonia, four parts boric acid, and one hundred and twenty eight parts distilled water, 45 to be convenient. The connection of the cells are such, as is customary with electrolytic rectifiers, that positive pulses pass from one side of the line through one of the outer 50 cells, and the coils of the relay, and thence through the intermediate cell to the other side of the line, negative pulses passing in similar fashion from the one side of the line through the center cell, the coils of the 55 relay, and the other outside cell, to the other side of the line; it being a characteristic of these electrolytic rectifiers that current can pass through any one cell of the rectifier in one direction only.

60 At low frequency (up to 60 cycles per

second) the maintenance of rectifiers such as above described is not excessive and their performance is fairly constant.

Relays 9, 10, 24 and 25 are provided with the hand switches 29 usually provided in relays of the McCulloh type, and described in the Hamblin patent referred to, for use in changing from metallic circuit to independent ground-return circuits. The use and effect of such switches being described in 75 said patent, in connection with switches corresponding to switches 13 and 28 herein, need not be described here.

Since inductive resistances, such as coils 5 and 7, offer only ohmic resistance to direct 80 currents, but offer very much greater resistance to alternating and pulsatory currents, and since condensers, such as 18 and 21, are "opaque" to direct current, but "transparent" to alternating currents, it is practicable, 85 by employing inductive resistances 5 and 7 of sufficient retardation, and by employing condensers 18 and 21, to completely isolate, operatively, the primary or direct-current circuit 4, and its receiving set 6, from the 90 alternating circuit 17, and its receiving set, 20, notwithstanding that both circuits and both receiving sets use the same line conductors 1, 2 and ground.

In Fig. 1 the switches 13 and 28 are indicated as in the position for normal working, that is to say, for working with a complete metallic circuit. In this art it is customary to speak of such a system as working "normally" when working on a complete metallic circuit, and to speak of the system as working as a McCulloh system, or, as the phrase is, "working McCulloh", when the system is working with ground return circuits. A large non-inductive resistance 30 105 (say a resistance of about 7000 ohms) is provided in the main circuit in order that the impedance of the line may be composed largely of resistance, the resistance of the line itself, in a system such as illustrated herein, being usually not greater than 1000 ohms. This enables the line relays to keep pace with rapid signals, and as the values of the line current are small, this resistance does not involve detrimental loss of power. 110 If this same resistance 30 were in the line when, by the operation of the switch 13, the direct current system is caused to operate as a McCulloh system, a practical difficulty would be presented, since in such case the 115 two ground return circuits of the direct current system, produced by reversing the switch 13 from the position shown in Fig. 1, would each contain less resistance than the metallic circuit used in normal operation, 120 for the metallic circuit contains both relays 9 and 10, each of large resistance, whereas the two ground return circuits, when the system is operating as a McCulloh system, 125 each contains but one of these relays. This 130

change of resistance, when converting the direct current system into two ground return circuits, if not counteracted, would cause the working current to change greatly when changing the system from normal working to McCulloh working, or vice versa, and so might give rise to various troubles. To obviate this difficulty I provide special non-inductive resistances 31, one for each such ground return circuit, which are of higher value than resistance 30, to compensate for the exclusion of one of the relays 9 and 10 from each ground return circuit, and I provide circuits, and, on switch 13, contacts therefor, whereby resistance 30 is in the line circuit during normal working, and one of these resistances 31 is in one ground return circuit, and the other resistance 31 is in the other ground return circuit, in McCulloh working. The circuits controlled by switch 13, by which resistance 30 is thrown out and resistances 31 thrown in, when changed from normal to McCulloh working, will be readily seen in Fig. 1. In practice these resistances 31 are of about 9000 ohms each; (it being understood that the values for resistance, referred to throughout this specification, are approximate, and are subject to variation in accordance with different operating conditions). On the alternating current side of the receiving apparatus, a similar arrangement of resistances is employed, the normal resistance 32 being arranged to be thrown out of circuit when the switch 28 is shifted for McCulloh working, and other somewhat greater resistances 33 being included, one in each of the ground return circuits thereby produced.

In order to compensate for the decrease in inductance in each ground return circuit, as compared with the inductance in the metallic circuit, due to the exclusion of one or the other of relays 9 and 10 from each ground return circuit of the direct current system, the inductance coils 7 at the receiving end of the direct current system are so arranged that an additional inductive value is added to each coil when the system is operating as two ground return circuits. This is accomplished by providing the coils 7 with separate windings, 7^a and 7^b, of which the two windings 7^a only are in circuit in normal or metallic return working, but when switch 13 is shifted for McCulloh working, windings 7^b are thrown into these circuits by the switch 13, each ground return circuit then including one winding 7^a and one winding 7^b connected in series. This arrangement obviates the greater leakage of alternating current through the direct current side which would otherwise occur during McCulloh working, without increasing the inductance of the direct current system during normal working.

65 As fully explained in the Hamblin patent

referred to, in case the circuit 4 should be broken but not grounded, at the instant of break the armature of relays 9 and 10 will drop and the signal receiving devices 11 and 12 will run continuously instead of intermittently, as in normal operation. The same will be true if a break should occur in one of conductors 1 and 2; and in such case the attendant will reverse the switch 13, which has the effect of dividing the circuit of the direct current system into two independent ground return circuits, of which one is served by relay 9 and register 11 and the other is served by relay 10 and register 11. In like manner, should a break without ground occur in the alternating circuit 17, the armatures of relays 24 and 25 will drop and signal receiving devices 26 and 27 will operate continuously instead of intermittently as in normal operation; and thereupon the attendant will reverse switch 28, which has the effect of converting the alternating current system into two independent ground return circuits. Should the break occur in conductor 1 or conductor 2, the armatures of all the relays 9, 10, 24 and 25 will drop, and the attendant will reverse both switches 13 and 28. Should a ground occur in the circuit 4 or in the circuit 17, this is evidenced at the central station by the operation of the signal receiving device 12, (in case circuit 4 is grounded) or by the operation of receiving device 27 (in case circuit 17 is grounded) and thereupon the attendant will not only reverse switch 13 or switch 28 as the case may be, but will also reverse the so-called "McCulloh" switches 29 on the relays 9 and 10, or 24 and 25, as the case may be, so that said relays then work through their back contacts instead of through their front contacts as formerly. If the ground should occur in one of conductors 1 or 2, the operator will reverse both switches 13 and 28 and all of the McCulloh switches 29.

110 In the following claims I use the term "rectifier" to designate a device which will convert current pulses of opposite directions into a current of one direction; that is to say, a direct current; and I use the term in contradistinction to mere asymmetric resistances which merely exclude from a circuit currents of one direction while permitting the passage of currents of the other direction.

115 What I claim is:

1. A telegraph system comprising in combination a line conductor, a source of supply of alternating current, a transmitter, a line relay and a current rectifier interposed between said relay and the line, whereby the alternating current of the line is transformed, as to said relay, into a direct current.

120 2. A telegraph system comprising in combination a line conductor, a source of supply

of alternating current, a transmitter, a line relay and an electrolytic rectifier interposed between said relay and the line, whereby the alternating current of the line is transformed, as to said relay, into a direct current.

3. A multiplex telegraph system, comprising in combination a direct current signaling system and an alternating current signaling system, said two systems comprising a common line conductor, said systems each comprising transmitting and receiving means and a source of current supply, and each comprising means for substantially isolating itself from the other system, the receiving means of the alternating current system comprising a neutral relay and a current rectifier interposed between such neutral relay and the line, whereby the alternating current of such alternating current system is converted, as to the said receiving relay of the alternating current system, into a direct current.

4. A multiplex telegraph system, comprising in combination a direct current signaling system and an alternating current signaling system, said two systems comprising a common line conductor, said systems each comprising transmitting and receiving means and a source of current supply, and each comprising means for substantially isolating itself from the other system, the receiving

means of the alternating current system comprising an electrolytic rectifier interposed between such neutral relay and the line, whereby the alternating current of such alternating current system is converted, as to the said receiving relay of the alternating current system, into a direct current.

5. A telegraph system comprising in combination a main metallic return circuit, a plurality of transmitters included in said circuit, and each comprising in addition to its connections to said circuit, a ground connection, a source of alternating current for said system, two neutral receiving relays, at least one of which is normally connected to said circuit, a switch and connections therefor arranged at will to convert the normal metallic return circuit including at least one of said relays, into two independent ground return circuits, each including one of said relays, and current rectifying means interposed between each such relay and the line connections thereof, whereby the alternating current of the line is converted, as to each such relay, into a direct current.

In testimony whereof, I affix my signature, in the presence of two witnesses.

JOSEPH F. D. HOGE.
